UNITED STATES PATENT OFFICE

HAROLD C. ROCKHOFF, OF TWO RIVERS, WISCONSIN

CIGARETTE-VENDING MACHINE

Application filed October 2, 1928. Serial No. 309,863.

This invention relates to a device especially designed for vending packaged articles such as cigarettes or the like, the primary object of the invention being to provide a vending device of this character wherein the packages held therein will automatically feed to the delivery end of the device when a package has been removed therefrom.

Another important object of the invention is to provide a device of this character which will be small and compact, the construction of the device being such that various brands of merchandise in package form may be contained in the device, while the width of the device is slightly greater than the width of one of the packages.

A further object of the invention is to display all of the different brands of cigarettes or packaged articles at the bottom of the device, so that a person removing a package may see at a glance and select the package to be removed.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a front elevational view of a dispensing device constructed in accordance with the invention.

Figure 2 is a side elevational view thereof.

Figure 3 is a vertical sectional view through the device.

Figure 4 is a bottom plan view thereof.

Figure 5 is a sectional view taken on line 5—5 of Figure 1.

Referring to the drawing in detail, the device embodies an elongated body portion having a rear wall 5 and side walls 6, the rear wall being preferably constructed of wood, while the side walls which are constructed of wood may be constructed of glass so that the articles may be viewed while in the device.

Elongated openings 7 are formed in the

side walls 6 when the walls are constructed of wood, so that the articles may be seen through the openings.

Extending throughout the length of the body portion and arranged in parallel spaced relation with each other, are partitions 8 preferably constructed of glass, the partitions dividing the body portion into a plurality of vertical compartments or passageways within which the articles are held.

These partitions slide in grooves formed in the side walls 6 of the body portion, so that they may be readily removed and replaced. At the lower ends of the compartments, are bottom members 9 that have their forward edges cut away as at 10 to define finger openings whereby a person may readily grip the packages or package to be removed without danger of breaking or tearing the wrapper from the package in order to remove it.

As shown, the forward lower edges of the side members or walls 6 are inclined towards the bottom of the device so that the delivery end of one compartment will not interfere with the removal of articles from the adjacent compartment.

Cut out portions 11 are formed at the lower ends of the side walls 6 so that portions of the ends of the packages will be exposed to be gripped by the person removing the packages.

Brace bars 12 are secured to the side walls 6 adjacent to the upper and lower ends thereof to further brace the side walls against lateral movement.

I claim:

A cabinet including an elongated body portion having side walls and a rear wall, a vertical partitioning member secured between the side walls and spaced from the rear wall defining a vertical compartment, vertical partitioning members spaced apart defining compartments therebetween, the lower end of one compartment being lower than the adjacent front compartment, bottom members having cut out portions and mounted at the lower ends of the compartments to support the weight of articles positioned in the compartments, the side walls of the cabinet having

cut out portions adjacent to the lower ends of the compartments to permit the articles in the compartments to be grasped by the fingers to remove the articles.

5 In testimony that I claim the foregoing as my own, I have hereto affixed my signature.

HAROLD C. ROCKHOFF.
